UNITED STATES PATENT OFFICE.

JACK A. PARTINGTON, OF SAN FRANCISCO, CALIFORNIA.

THEATRICAL NOVELTY.

Application filed March 24, 1925. Serial No. 17,999.

To all whom it may concern:

Be it known that I, JACK A. PARTINGTON, a citizen of the United States, residing at the city and county of San Francisco and State of California, have invented new and useful Improvements in Theatrical Novelty, of which the following is a specification.

This invention relates to theatrical novelties and particularly to a movable platform which normally rests on the stage of the theater and mechanism cooperating with the platform and including means for moving the same both horizontally and vertically. Many theatrical acts require additional stage room, quick changes of additional stage settings, the provision of more than one scene simultaneously, the quick arrangement of such settings in a manner wherein the same will be most clearly observed by the audience, etc. It is the primary object of my invention to provide a theatrical novelty wherein these and other advantageous features are most efficiently obtained.

More specifically, my invention comprises a movable platform, mounted on tracks extending forwardly and rearwardly on the stage of the theater. Power means is provided for moving the platform to different positions along the tracks. Other power means, as hydraulic rams, is provided beneath the stage for raising the platform vertically to a higher level above the stage, such power means being preferably provided at different positions along the tracks whereby the platform can be raised from its different positions on the stage. As hereinafter more specifically described, this platform may carry an orchestra, a corps of actors, a stage scene or any similar setting. The arrangement is such that the platform can be quickly moved both horizontally and vertically to various positions on the stage thereby accomplishing the various objects and advantages hereinafter described.

With the above and other objects in view, as will hereinafter appear, my invention consists in the features of construction and operation set forth in the following specification and illustrated in the accompanying drawings. In such drawings annexed hereto and forming a part of this specification I have shown certain specific embodiments of my invention, but it will be understood that the invention can be otherwise em-

bodied and that the drawings are not to be construed as defining or limiting the scope of the invention, the claims appended to this specification being relied upon for that purpose.

Referring to the figures of the drawings:

Fig. 1 illustrates a sectional view through a stage showing one of my movable platforms in end elevation.

Fig. 2 is a similar view showing the movable platform in other positions and in combination with a second and auxiliary movable platform.

Fig. 3 is a view similar to Fig. 1 showing the main movable platform in another position.

Fig. 4 is a fragmentary plan view of the stage showing my movable platforms and the various parts thereof in detail.

Fig. 5 is a sectional view through the main movable platform and stage and showing the platform-lifting mechanism beneath the stage.

Fig. 6 is a detail view showing one form of curtain-operating mechanism for the curtain on the movable platform.

Fig. 7 is a similar view showing another form of curtain-operating mechanism.

Fig. 8 is a sectional view through the movable platform and stage and showing the platform-lifting mechanism in engagement with the platform.

Fig. 9 is an enlarged sectional detail view illustrating shock absorbing means in the platform-engaging end of the lifting rams.

Fig. 10 is a plan view of the platform-lifting means.

Referring more specifically to the drawings by reference characters, 1 indicates the stage of a theater having a pair of tracks 2 extending forwardly and rearwardly through the center thereof. My main movable platform 3 is carried on a plurality 100 of wheels 4 riding on these tracks. As illustrated, the platform is of a length extending substantially across the width of the stage. The platform is preferably moved along the track by an electric motor 5 operatively connected to the front wheels 4 through gearing 6 and a shaft 7.

As illustrated in Fig. 10, the stage is provided with front and rear pairs of stops 8 and 9 respectively cooperating with the front and rear stops 10 and 11 of the platform. The platform is normally adapted

to occupy one of these extreme positions. A power means, now to be described, is provided beneath the stage at these places for elevating the platform. This power means 5 preferably comprises front and rear pairs of hydraulic rams 12 and 13 respectively beneath the extreme front and rear platform portions of the stage.

The platform 3 is of rigid steel frame 10 construction, as illustrated, and adjacent each end thereof is provided a supporting bracket 14 having a ram receiving socket 15 therein. This supporting bracket 14 is riveted to and between two steel beams 16 15 having their ends riveted to the two steel beams 17 in turn having their ends riveted to the main outside steel beams or girders 18 of the platform. The sockets 15 are each of a shape and size to accurately receive a 20 lifting ram therein, as shown in Figs. 8 and 9.

As shown in Fig. 9, the upper end of each ram extends through a ring plate 19 secured to the stage floor and having a downwardly extending flange 20 beveled off at 21. The upper end of each ram comprises two tubular steel shells 22 and 23 supporting a ring-like plate 24 at their upper ends. A compression spring 25 is mounted within the 30 shell 23 between a bottom plate 26 and a movable block 27. A pin 28 is secured to the upper wall of the socket 15 and extends downwardly in a manner cooperating with the block 27. When the ram is in its normal and lowermost position, the top surfaces of the plate 24 and block 27 are substantially flush with the stage floor. When the ram moves upwardly into the socket the block 27 engages the pin 28 and the spring 40 25 is compressed, thereby acting as a shock absorber relieving the engagement of the ram with the platform.

The rams 12 and 13 operate respectively in cylinders 29 and 30 within a concrete 45 foundation 31, a dash pot arrangement 32 being provided in the bottoms of the cylinders to cushion the rams. Fluid pressure is supplied to the cylinders from an elevated tank 33 having a downwardly extending 50 supply pipe 34. This pipe is in communication with a pipe 35 in communication with two rearwardly extending pipes 36 and two forward pipes 37 controlled respectively by valves 38 and 39. A pipe 40 connects the pipe 35 with a lower tank 41 and two valves 42 and 43 respectively control the communication to the tanks 33 and 41. A motor 44 operates a pump 45 to pump oil or other pressure fluid used from the tank 41 to the tank 33 under pressure.

The frame of the platform 3 is provided with a curtain 46 rolled on a roller 47. This roller can be controlled manually by a cord 48 shown in Fig. 7 or automatically 65 by a weight 49 shown in Fig. 6. The weight

49 is hung on a cord 50 attached to the stage floor at 51 and extending over a pulley 52. The pulley 52 is connected by a chain 53 to the curtain roller. As the platform is raised and lowered the chain is 70 automatically operated to lower and raise the curtain. This automatically operating device can be used only when the platform is not to be moved horizontally, since an attachment must be made to the floor at 51. 75

During the movement of the platform 3 the electric cords 54, 55 and 56 to the motor 5 and lighting effects on the platform are automatically cared for by winding reels 57, 58 and 59, each reel being kept tensioned 80 in a winding-up direction by a spring 60 on a rod 61 connected to the reel by bevel gears 62. The cords run over pulleys 63 and between pulleys 64 and thence to a socket connection in the stage floor. When the platform is moved forwardly and backwardly the cord is guided by the pulleys 64.

The operation of my invention is as follows: The platform 3 can be moved to either its forward or rearward positions by 90 means of the motor 5, the stops 8 and 9 acting to accurately position the platform over the front and rear lifting rams. The pump 45 forces fluid to the elevated tank 33 under pressure. By controlling the valves 95 above described either the front or rear rams 12 and 13 can be raised and elevate the platform to a desired position above the stage floor. When lowering the rams the fluid empties into the tank 41 from which it is pumped to the tank 33. It is believed that the operation of this mechanism will be understood without further description herein.

In Figs. 1, 2 and 3 of the drawing, I have, for the purpose of giving a general idea of the use of my invention, diagrammatically illustrated certain positions that my movable platform may assume. It will, however, be understood that the parts may be placed in relations other than those illustrated and that my invention is in no manner limited to these particular effects shown and described.

The front of the stage is indicated at 65 and the front curtain at 66. In Fig. 1, I have illustrated the platform 3 as resting on the stage in its forward position. We will assume that in this act the orchestra occupies the platform. When the curtain 66 goes up the orchestra plays an opening number. Thereafter the motor 5 is operated to move the platform to its rearward position and the rams 13 are operated to raise the platform to the position illustrated in dash lines, the curtain 46 being drawn down at this time. This operation will preferably be performed during the last part of the orchestral number since the movement of the platform in no manner affects the orchestra or its act. The front of the stage 110 115 120 125 130

is thus quickly cleared without any interruption of the show and is ready for the next act, and the orchestra, which ordinarily accompanies the act, is in an elevated position 6 in full view of the audience. Thus the audience has a clear view of both the act and the accompanying orchestra which are on different levels, the main act being in the foreground.

10 It may furthermore be stated that while the last mentioned act is going on, a scene may be set beneath the platform 3 behind the curtain 46. When the act is finished, the curtain 46 may be raised and the next 15 scene enacted beneath the platform, which is, of course, in full view of the audience.

In Figs. 2 and 4 I have illustrated a second platform 67 on the tracks 2, this platform being shorter than the platform 3 20 and of a length to pass between the pairs of rams 12 and 13. The rear curtain is indicated at 68. During one of the acts above described the platform 67 which is in the rear of the stage may be prepared for a 25 scene. Then, after the platform 3 is elevated the curtain 46 can be raised and the platform 67 with its scene thereon rolled to the front of the stage, the platform 67 being provided with a motor similar to the 30 motor 5. This scene and the orchestra on the elevated platform 3 are thereupon both in clear view of the audience as illustrated in dash lines. Before raising the curtain 46 a scenic background 70 will be placed 35 about the rear portion of the platform 67.

In Fig. 3, I have illustrated the platform 3 in its front elevated position. During an 40 orchestral number or a portion thereof, the platform may be elevated to this position and a scene arranged beneath the platform, the curtain 46 being drawn down at this time. The scenery may be mounted on 45 rollers and include a background 69. When the orchestral number is finished, the curtain 46 can be raised to show this scene. Thus, this act and the accompanying 50 orchestra are both at the front of the stage in direct view of the audience, the act and the orchestra being on different levels.

55 Many and various other similar relations may be provided by the use of my invention as will be readily understood.

Having thus described my invention, what I claim and desire to secure by Letters 55 Patent is:—

1. A theatrical novelty comprising in combination with a stage and a track thereon, a platform supported on and movable along the track to a plurality of positions on the stage, and power means normally beneath the stage for elevating the platform from the track and stage in one of such positions.

2. A theatrical novelty comprising in 65 combination with a stage, a platform mov-

able to a forward position and a rearward position on the stage, power means for so moving the platform, fluid operating means beneath the stage for elevating the platform in one of such positions, and means carried by the platform and cooperating with the fluid operated means for holding the platform in place thereon.

3. A theatrical novelty comprising in combination with a stage, a platform extending substantially across the width of the stage and movable to a forward position and a rearward position on the stage, power means for so moving the platform, and fluid operating means beneath the stage for elevating the platform in both such positions.

4. A theatrical novelty comprising in combination with a stage, tracks on the stage, a movable platform carried by wheels riding on the tracks, an electric motor carried by the platform and connected to certain of the wheels for driving the platform, and hydraulic rams beneath the stage adapted to raise the platform above the stage.

5. A theatrical novelty comprising in combination with a stage, a platform movable to a plurality of positions on the stage, an electric motor carried by the platform for moving the platform forwardly and rearwardly to a plurality of positions on the stage, and power means beneath the stage for elevating the platform in these positions.

6. A theatrical novelty comprising in combination with a stage, a platform movable to a forward position and a rearward position on the stage, power means beneath the stage for elevating the platform to a higher level in one of such positions, a curtain hung from the front of the platform for hiding the space beneath the raised platform, and means for operating the curtain.

7. A theatrical novelty comprising in combination with a stage, a platform movable to a plurality of positions on the stage, an electric motor carried by the platform for moving the platform forwardly and rearwardly to a plurality of positions on the stage, a supporting socket member carried by the platform at each end thereof, and a pair of hydraulic rams beneath the stage and adapted to engage in the said sockets to raise and support the platform above the stage.

8. A theatrical novelty comprising in combination with a stage, a pair of hydraulic rams beneath the stage adjacent the opposite sides thereof, a platform over the rams, forwardly and rearwardly extending tracks on the stage between the rams, a platform carried on the tracks and of a width to pass between the rams, the second mentioned platform normally being to the rear of the

rams and being adapted to be moved forward therebetween when the first mentioned platform is raised to a higher level by the rams.

5. 9. A theatrical novelty comprising in combination with a stage, forwardly and rearwardly extending tracks on the stage, a steel frame platform extending substantially across the width of the stage and

mounted on wheels on the track, means for moving the platform on the track to forward and rearward positions on the stage, a pair of hydraulic rams beneath the stage at each of such positions, and means whereby the rams can be elevated to lift and support the platform above the stage at both such positions.

JACK A. PARTINGTON.
